UNITED STATES PATENT OFFICE.

THELO GLENN WHITE, OF CEDAR RAPIDS, IOWA.

BALING-PRESS.

1,130,780.

Specification of Letters Patent.

Patented Mar. 9, 1915.

Application filed June 1, 1914. Serial No. 842,213.

To all whom it may concern:

Be it known that I, THELO GLENN WHITE, a citizen of the United States, and residing at Cedar Rapids, in the county of Linn and State of Iowa, have invented certain new and useful Improvements in Baling-Presses, of which the following is a specification.

This invention relates to certain new and useful improvements in baling presses.

10 The present invention is an improvement upon the baling press shown, described, and claimed in the patent issued to J. C. Fulker-
son and T. G. White, October 29, 1912,
#1,042,544.

15 According to my invention, I provide a baling press particularly adapted for the baling of empty bags, such as those that are used in the shipment of cement and the like.

The present invention has for its object to 20 provide in connection with a baling press of the type in the above-mentioned patent, improved means whereby the bags are given a different folded position to present the bags in rounded form at the time of 25 tying the same together.

A further object of the invention is to pro- 30 vide a baling press formed of a plurality of foldable board sections with means overlying the board sections to prevent the bags being folded from being caught in the hinge joint.

A still further object of the present im- 35 provements is to provide tie-wire supports carried by the foldable leaf sections that will cross the ends of the tie-wires when the press is folded to present the ends in a position to be tied.

It is also the object of the present inven- 40 tion to provide a false bottom section, or a section different in size, and preferably smaller, than the main press section, to be placed on the main press section and used in connection with the folding of bags smaller in size or a smaller number of bags.

5 With the above general objects in view and others that will appear as the nature of the invention is better understood, the same consists in the novel construction, combina- 55 tion and arrangement of parts to be herein-
after more fully described and then claimed.

In the accompanying drawing, which shows the preferred embodiment of the present improvements in connection with the before-mentioned patent, and to which 65 reference is had herein by like characters designating corresponding parts throughout

the several views: Figure 1 is a top plan view of the baling press in open position with the angle plates covering the hinge connection. Fig. 2 is a side elevational view 60 of the same. Fig. 3 is an enlarged perspective view of a portion of the foldable leaf sections, showing the position assumed by the angle plates and the improved tie-wire support. Fig. 4 is an enlarged detail per- 65 spective view of a wear plate. Fig. 5 is a vertical cross-sectional view with a false bottom in position, and the press folded, and, Fig. 6 is a detail perspective view of a portion of an angle plate. 70

The present invention embodies the main working parts of the construction shown, described, and claimed in Patent 1,042,544, with the improvements applied thereto in a manner which will render the present de- 75 vice more thorough and efficient in its operation.

Referring more in detail to the accom- 80 panying drawing, the reference numeral 10 designates in general the supporting frame shown as embodying the legs 11, and central cross-bar or brace 12. Mounted on the frame 10 are the foldable leaf sections constituting the table or support for the bags or other articles to be folded, and comprises 85 more in detail, the stationary center leaf section 13 to be secured to the frame 10 in any suitable manner, and having hinged to the lateral sides thereof as at 14, the side swinging leaf sections 15. 90

The construction so far described is what is substantially shown in the above-men- 95 tioned patent, and a material improvement is the adaptation of means to cover the hinge joint to prevent the bags or other articles from being caught therein, and at the same time reduce in size the corners, to add a rounded edge to the bags, such means comprising an angle plate 16 as shown in Fig. 6, having the short arm 17 received in the longitudinal 100 slots or grooves 18 arranged parallel and adjacent to the hinge connection 14, as clearly shown in Figs. 1 and 3. These angle plates 16 are formed of resilient material and when the side leaves 15 are folded as 105 shown in Fig. 3, the plates 16 are caused to assume the position shown in said figure, owing to the resiliency thereof, thereby re- 110 ducing the sharp corners to rounded ones and covering the hinge connection to pre- 115 vent the bags from being caught therein.

The leaf members 15 are caused to assume

the position at right angles to the stationary central leaf section 13 and the mechanism for accomplishing this result consists of a pair of guide bars 19 operating in connection with a cross-head 20 carrying a roller 21 at each end thereof, the cross-head 20 having a rod connection 22 with a treadle 23. Pivoted as at 24 to the cross-bar 12 and outwardly as shown in Fig. 5, is a pair of arms 25 having the lower ends thereof extending downwardly to a point adjacent the guide bars 19 to be engaged by the rollers 21. The inner faces of the lower ends of the arms 25 are flattened as at 26 to adapt the same to lie parallel when in the position shown in Fig. 5, so that the rollers 21 engage the flattened sides at practically a dead center to prevent the raising of the cross-head 20 without a slight upward movement being imparted to the treadle 23. The arms 27 beyond the pivot point 24 are suitably curved as at 27 to provide a clearance for the side leaf sections 15, and carry at their outer ends rollers 28. Wear plates 29 are secured as at 30 to the bottom faces of the side leaf sections 15, and consist of angle plates, as clearly shown in Fig. 4 on which ride the rollers 28 carried by the arms 25, the lower ends of the wear plates 29 being cushioned by a spring 31 seated in a suitable recess formed in the leaves 15 and engaging at the other ends the wear plates. By such a construction, the side leaf sections 15 are easily brought to the position shown in Fig. 5 with all unnecessary strain and wear on the parts obviated by the spring-pressed wear plates and curved arms 25.

As an improvement over the manner of holding the tie-wires shown in the above-mentioned patent, I provide a single piece wire clasp 32, as shown in Fig. 3. This clasp consists of a single piece of wire bent upon itself as at 33 and having the bent portion received within a socket 34 provided in the inner face of the side leaves 15, the said wire being further bent to form a pair of contacting loops 35 with the ends thereof provided with eyes 36, one of which is secured to the edge of the side leaf 15 while the other eye is secured to the inner face of said section. Tie-wires 37 are positioned on the leaf sections 13 and 15 and supported by the clasps 32, the loops 35 of the clasps being directed inwardly so that the tie-wire placed therein as shown in Fig. 3, will be directed inwardly to cross the other end of the wire and be in position to be joined or tied. The present invention also employs the presser rod 38 in connection with the adjustable bolts 39 carried by the central leaf section 13 around which the bags are folded.

By reference to Fig. 5, it will be seen that there is provided a false bottom for the press which will better enable the folding of bags of smaller size or a smaller number

of bags. The construction of the false bottom is similar to the main folding leaf sections, and comprises the center section 13' having hinged to the lateral sides thereof the side leaf sections 15', the central section 13' being slotted in a manner similar to the leaf section 13 for the reception of the angle plate 16'. The bottom face of the central section 13' carries cleats 18" which may have a suitable dowel connection with the main leaf section 13. Clasp members 32', similar in construction to the clasp 32, are carried by the leaf sections 15' and operate in a like manner. It will be noted that each machine may be provided with a plurality of false bottom sections of different sizes for the purpose above stated.

It is believed that the operation of the device will be clearly evident from the above description and showing, and further explanation is thought unnecessary.

While the preferred embodiments of the improvements are herein shown and described, I do not wish to confine myself to the exact details of construction shown, as various forms, modifications and arrangement of the parts as shown may be had without departing from the spirit and scope of the invention as claimed.

What I claim as new is:

1. In a baling press, a table formed of a plurality of hinged sections, and a plate mounted to overlie the hinge connection between the sections.
2. In a baling press, a table formed of a central fixed section, side sections hinged to the central section, said central section having a longitudinal groove adjacent each side edge, and resilient angle plates mounted in the grooves and adapted to overlie the hinge connections.

3: In a baling press, a table formed of hinged sections, a presser bar arranged above the sections, pivoted arms having the outer ends engaging the hinged sections, and cushioned wear plates disposed between the hinged sections and the arms.

4. In a baling press, a supporting frame, a table comprising a stationary leaf section and two hinged leaf sections, resilient angle plates carried by the stationary section and overlying the hinge connections, a removably mounted rod above the stationary section, and means for moving the hinged sections to a position at right angles to the stationary section and co-operating to hold the hinged sections in folded position.

5. The combination with a baling press having a stationary section and two hinged sections, of a false bottom therefor, said false bottom comprising a central section positioned above the said stationary section, side sections hinged thereto, and plates carried by the central section adapted to overlie the side hinge connections.

6. In a baling press, a table formed of a central section and side sections hinged thereto, and resilient plates carried by the central section and overlying the hinge connections, the plates assuming an angular position when the sections are folded.

7. In a baling press, a table formed of a fixed section and hinged side sections, pivoted arms having the outer ends engaging the hinged sections, wear plates disposed between the hinged sections and arms, com-

prising channel irons pivoted at their outer ends to the hinged sections, and springs carried by the hinged sections engaging the free ends of the wear plates.

In testimony whereof I affix my signature in presence of two witnesses.

THELO GLENN WHITE.
